UNITED STATES PATENT OFFICE.

ERNEST E. TRAFTON, OF PORTLAND, MAINE.

AUTOMATIC CUT-IN FOR TELEPHONE REINFORCING DEVICES.

1,186,864.

Specification of Letters Patent. Patented June 13, 1916.

Application filed May 7, 1912. Serial No. 695,649.

To all whom it may concern:

Be it known that I, ERNEST E. TRAFTON, a citizen of the United States, residing in Portland, county of Cumberland, and State of Maine, have invented a new and useful Improvement in Automatic Cut-Ins for Telephone Reinforcing Devices, of which the following is a description.

This invention relates to apparatus for reinforcing or intensifying the electrical impulses received over a telephone line from any distance, and has special reference to means applicable to the usual "desk-stand" transmitter to adapt the same for use in connection with my reinforcing apparatus made the subject of my application filed January 10, 1912, No. 670,387.

Among the objects of my invention may be noted the following: to provide means, applicable to the well-known desk-stand transmitter of telephone systems, which will prevent wasting of the batteries of my reinforcing apparatus when the latter is inserted in the telephone circuit; to provide means by which the desk-stand transmitter will automatically bring into action my reinforcing apparatus, or other impulse reinforcing device, when said transmitter is brought into use; to provide a device applicable to the desk-stand transmitter, for the purpose above stated, without changing the appearance, form, or structure of said transmitter; to provide a means, applicable to a desk-stand transmitter, which may be operated automatically, through the medium of the receiver-hook, to open and close the battery circuit of my aforesaid reinforcing apparatus; and to provide a simple, cheap and efficient means, for application to desk-stand transmitters, by which to set my reinforcing apparatus in operation when the telephone receiver is lifted from the hook.

With the above objects in view, and others which will be detailed during the course of this description, my invention consists in the parts, features and elements and combinations of elements hereinafter described and claimed.

To give a clear understanding of my invention, I have provided drawings wherein:

Figure 1 is a perspective view showing a desk-stand transmitter with my reinforcing apparatus connected therewith according to my invention; Fig. 2 is a sectional, front elevation showing my invention applied to

the transmitter-stand; Fig. 3 is a sectional, side elevation, similar to Fig. 2, with the receiver omitted; and Fig. 4 is a diagrammatic view of the circuits and instruments laid out according to my invention.

Primarily, it should be understood that my reinforcing apparatus, made the subject of my aforesaid application, intensifies and reinforces the electrical impulses received over a telephone line and may be in shunt, or in parallel, with the telephone receiver and in series with the main line, and that, in practical use of the instrument, it has been found that the operator, in his hurry, or through carelessness, will not replace the receiver of the reinforcing apparatus to its proper place. This has caused a great deal of trouble with the instrument because the batteries waste rapidly and the efficiency of the reinforcing apparatus is, consequently, diminished. Moreover, train-despatchers have no time to bother with a lot of instruments and devices and have found fault with being compelled to think of always hanging up the receiver of the reinforcing apparatus in order to keep the instrument in condition and always find it so when required.

My present invention overcomes the objections noted and requires no care or attention whatever on the part of the operator.

Referring to the drawings, the numeral 1 indicates the base of the desk-stand, 2 the tubular upright, 3 the transmitter, 4 the receiver, and 5 the receiver-hook.

My reinforcing apparatus is indicated by 6, and is always sealed, as at 7, to prevent tampering with the same.

The receiver of the reinforcing apparatus is indicated at 8, and may be disposed in any way convenient for the operator. When the receiver 4 is lifted from or placed on the hook 5, it makes or breaks a contact at 9, through the medium of the controller-spring 10, engaging the hook at the point 11, the hook being pivotally supported at 12. The insulation for the controller-spring and contacts is as usual and the leads of the transmitter are indicated at 13, and those of the receiver are indicated at 14, 15.

Referring to Figs. 2 and 3, the contacts 16, 17, are shown insulated at 18, from the contacts 9, and from each other in suitable manner, and all supported by the same plate 19, extending lengthwise of upright 2. This makes a compact arrangement and en-

ables the spring 10, under the action of the hook 5 to control the two sets of contacts at one time by merely lifting and replacing the receiver 4.

- 5 In the diagram of Fig. 4, it will be seen that the "tip" lead of the telephone line is indicated at *a*, and runs to the transmitter 3, through lead 13, through the controller-spring 10, contacts 9, and "ring" lead *b*, 10 through the primary of the induction-coil. Across the main line is bridged the circuit containing the bells and condenser shown by the conventional signs. In series with the condenser, through the lead *c*, is the secondary 15 of the induction-coil and the standard receiver 4, the circuit through which, by way of lead 15, is opened and closed by operating the hook 5, and the return lead of which circuit is back through the primary 20 to the main line. The receiving element of my reinforcing apparatus, the latter being indicated by *d*, is bridged across the terminals of the receiver 4, through the medium of the leads *d* and *e*. The reinforcing apparatus 25 circuit includes in series the receiver 8, battery 20, the variable-resistance button 21, and frame of the said reinforcing apparatus, the circuit from the battery being indicated by *f*, and running to the said button 21, and 30 from the frame of the reinforcing apparatus through the lead *g* to the inner one of the contacts 16, and from the outer of the contacts 17, back through the lead *h* to the receiver 8.
- 35 From the foregoing, it will be seen that the arrangement of the parts is such that, when the operator desires to use the ordinary telephone for either transmitting or receiving a message, the same action on his 40 part which brings into play the functions of said telephone will automatically bring into play and action my reinforcing apparatus, since, when he receives the signal of a message, or desires to transmit a message, 45 and lifts from the hook 5 the receiver 4, my reinforcing apparatus is automatically set in operation through the medium of the controlling-spring 10, operating upon the contacts 9, and the latter upon the contacts 16 50 and 17. This automatic operation, of the two sets of contacts, brings my reinforcing apparatus into operation without any further effort or concern on the part of the operator and immediately imposes upon the 55 telephone circuit the reinforcing and intensifying action of my reinforcing apparatus.
- In the foregoing description, I have described my invention as having particular 60 reference to cutting into the telephone circuit automatically my reinforcing and intensifying device, which has become known as a Relayfone and made the subject of my aforesaid application; but I desire it to be 65 distinctly understood that my present invention is not limited to bringing into play

the particular form of instrument, in connection with which I have illustrated my invention.

My present invention comprehends, broadly the idea of means of providing a 70 device or mechanism automatically operating, through the medium of the desk-stand of the ordinary telephone system, any form of means, mechanism, or device capable of magnifying, intensifying, or reinforcing the 75 electrical impulses passing over the lines of the telephone system. Hence, in my claims, I purpose covering my said invention in the broadest possible terms, as I believe myself to be a pioneer in this connection. 80

Having thus described my invention, what I claim and desire to secure by Letters Patent is:

1. In combination with a telephone set and its circuit, which latter is normally 85 open; a reinforcing apparatus in shunt to the receiver of said set; an auxiliary receiver; a battery in series with the latter having a circuit including said reinforcing apparatus and being normally open; and 90 means for simultaneously closing both of the open circuits.

2. In combination with a telephone set and its circuit, which latter is normally open; a reinforcing apparatus in shunt to 95 the receiver of said set; an auxiliary receiver; a battery in series with the latter having a circuit including said reinforcing apparatus and being normally open; and means for closing both the open circuits including a member for supporting the receiver of the said set. 100

3. In combination with a telephone set and its circuit, which latter is normally open; a reinforcing apparatus in shunt to 105 the receiver of said set; an auxiliary receiver; a battery in series with the latter having a circuit including said reinforcing apparatus and being normally open; a pivotally supported hook for sustaining the receiver of the said set; and means co-operating with said hook for closing both of the normally open circuits when the said hook is lifted. 110

4. In combination with a telephone set and its circuit, which latter is normally open; a reinforcing apparatus in shunt to 115 the receiver of said set; an auxiliary receiver; a battery in series with the latter having a circuit including said reinforcing apparatus and being normally open; and means including a resilient member arranged co-operatively with the terminals of one of the open circuits and normally out of contact with the latter, and a device for causing said resilient member to close the said two open circuits by engagement thereof with said terminals. 120

5. In combination with a telephone system including a deskstand, transmitter and 125

receiver, together with their circuits; of terminals for the receiver comprising normally separated resilient members; a reinforcing apparatus in shunt to the said receiver; an auxiliary receiver and a battery in series in a circuit which also includes in series the reinforcing apparatus and the terminals of which circuit comprise normally separated resilient members arranged in co-operative relation to the resilient members of the main receiver within the said stand; means for supporting the main receiver pivotally mounted within the said stand; and a device co-operating with the said supporting means for shifting all of the said resilient terminal members so as to close the said two open circuits.

6. A telephone system comprising the usual set and circuits therefor, in combination with a reinforcing apparatus in shunt to the receiver of the set and in series in the main circuit; an auxiliary receiver and source of electrical energy in series in a circuit which also includes said reinforcing apparatus and which said circuit is normally open and the terminal members of which are arranged in co-operative relation to the terminal members of the receiver of said set; and automatic means for closing the circuit of said receiver and the circuit of the auxiliary receiver and connect the two receivers electrically.

7. In a telephone system and in combination with the telephone set thereof and its several circuits; a reinforcing apparatus in shunt to the receiver of said set and in series with the main circuit of the system; an auxiliary receiver having in series therewith a source of electrical energy and a circuit, which also includes a reinforcing apparatus in series with the latter two elements and the terminals of which are normally separated and arranged in co-operative relation to the normally separated terminals of the members of the said set; and automatic means for closing all the said terminals, so as to simultaneously close the three open circuits

to connect the reinforcing apparatus in series in the main circuit and in shunt to the main receiver and connect the auxiliary receiver and source of electrical energy in series with the main receiver.

8. The combination, in a telephone system, of a main receiver, a stand carrying a movable member for supporting the main receiver, a pair of movable contacts for the circuit of the main receiver carried by the stand, an auxiliary receiver, a second pair of movable contacts for the circuit of the auxiliary receiver carried by the stand, and a releasable member normally tending to force said pairs of contacts together, said member being controlled by the movable member whereby, when the main receiver is lifted, the circuit thereof and of the auxiliary receiver will be automatically closed, and when the main receiver is hung up said circuits will be automatically broken.

9. The combination, in a telephone system, of a main receiver, a stand carrying a movable member for supporting the main receiver, a pair of movable contacts for the circuit of the main receiver carried by the stand, an auxiliary receiver, a second pair of movable contacts for the circuit of the auxiliary receiver carried by the stand, a releasable member normally tending to force said pairs of contacts together, said member being controlled by the movable member whereby, when the main receiver is lifted, the circuit thereof and of the auxiliary receiver will be automatically closed, and when the main receiver is hung up said circuits will be automatically broken, and insulating means extending between said contacts for electrically separating one pair of said contacts from the other.

In testimony whereof I have hereunto signed my name in the presence of two subscribing witnesses.

ERNEST E. TRAFTON.
